LOOSELEAF BINDER

Douglas R. Cleminshaw, Syracuse, N.Y., assignor to Hall and McChesney Inc., Syracuse, N.Y.

Filed June 9, 1971, Ser. No. 151,631

Term of patent 14 years

Int. Cl. D19—04

U.S. Cl. D97—2

FIG. 1

FIG. 2

FIG. 3

FIG. 4

FIG. 5

FIG. 6

FIG. 1 is a front perspective view of a looseleaf binder embodying my new design;

FIG. 2 is a front elevation thereof;

FIG. 3 is a right side elevation thereof with reference to FIG. 2;

FIG. 4 is a rear elevation thereof;

FIG. 5 is a left side elevation thereof with reference to FIG. 2; and

FIG. 6 is a bottom plan view thereof with reference to FIG. 4, the top plan view being identical.

I claim:

The ornamental design for a looseleaf binder, substantially as shown and described.
